(No Model.)

W. E. PRALL, Jr.

STEAM MOTOR FOR STREET CARS.

No. 393,263.

Patented Nov. 20, 1888.

UNITED STATES PATENT OFFICE.

WILLIAM EDGAR PRALL, JR., OF WASHINGTON, DISTRICT OF COLUMBIA,
ASSIGNOR TO WILLIAM E. PRALL, OF SAME PLACE.

STEAM-MOTOR FOR STREET-CARS.

SPECIFICATION forming part of Letters Patent No. 393,263, dated November 20, 1888.

Application filed May 16, 1888. Serial No. 273,958. (No model.)

To all whom it may concern:

Be it known that I, WILLIAM EDGAR PRALL, Jr., a citizen of the United States, residing at Washington, District of Columbia, have invented certain new and useful Improvements in 5 Steam-Motors for Street-Cars; and I do declare the following to be a full, clear, and exact description of the invention, such as will enable others skilled in the art to which it appertains 10 to make and use the same, reference being had to the accompanying drawing, and to the letters and figures of reference marked thereon, which form a part of this specification.

The object of the invention is to provide 15 means adapted to move by the aid of steam-power ordinary street-cars—such as are usually drawn by horses—and to provide for this purpose an apparatus that can be safely and readily managed by persons of ordinary intelligence, and in which the generation of steam 20 can be instantaneously begun or stopped at will by simply manipulating a lever, and in which all danger of excessive pressure is avoided and also all disagreeable odors, 25 vapors, and noise.

The invention consists in certain devices and combinations, hereinafter described and pointed out.

In the accompanying drawing, which forms 30 part of this specification, the figure represents a side view, partly in section, of a car and of my improved apparatus applied thereto, and 1 indicates a hot-water reservoir; 2, a gasoline-tank; 3, a device for vaporizing the oil by 35 means of hot water; 4, a steam-generator, and 5 a steam-cylinder having connection to drive the car.

The hot-water tank communicates with a 40 smaller tank or receptacle, 6, by means of a pipe, 7, having a cock or valve, 8, and said smaller tank communicates with the steam-generator by means of a pipe, 9, having a needle or pressure-reducing valve, indicated at 45 10. The oil-tank communicates with what may be styled a "cooling-tank," 11, by means of pipe 12, which may be provided with a stop-cock. Pipe 12 communicates with the cooling-tank and extends into the interior of the small hot-water receptacle 6, where it is formed 50 into a coil of zigzag or equivalent form, and it is continued to and communicates with an an-

nular chamber, 13, which surrounds receptacle 6. A bent pipe, 14, connects chamber 13 with a mercury seal, 15, or equivalent, as indicated. The space above the mercury is 55 connected by means of pipe 17 with the head or cross tube 18, from which extend the burner-tubes 19, provided with burner-outlets, as indicated.

20 indicates a valve or cock for stopping the flow of gasoline-vapor in pipe 17, and 21 a small by-pass pipe, the object of which is to supply gasoline-vapor or other fuel to a lighting-burner consisting of burner-tubes having 60 comparatively small openings arranged adjacent to the main burner-openings.

16 is a vapor or gas pipe to supply lighting-burners, as shown.

22 indicates a coil of pipe, preferably made of copper, about three-fourths of an inch in 70 diameter, which communicates with pipe 9, and, through said pipe and receptacle 6 and pipe 7, with tank 1. There is preferably arranged under each of several sections of said pipe an asbestos shield, which serves the 75 double purpose of protecting the pipe from the direct action of the flame and of compelling a tortuous circulation of the products of combustion to bring them in repeated contact with the coil.

23 is a pipe forming an extension of the steam-generating coil and arranged to convey steam to the steam-chest of the cylinder. This pipe is provided with a valve or cock, 24.

The cock 8 in the hot-water pipe, the cock 80 20 in the vapor-pipe, and the cock 24 in the steam-pipe are all opened or closed simultaneously by rod 25, having lever-handle 26 conveniently located, as on the platform of the car. The piston-rod of the steam-cylinder is 85 connected with the axle or wheels of the car in any approved manner. Sprocket wheels and chains are indicated in the drawing.

The water-tank 1 may be made to hold thirty 90 or forty gallons of water under a pressure of about three hundred pounds and at a temperature of about 400° Fahrenheit. It can be filled through the stop-cock 29. It is preferably provided with a non-conducting jacket of asbestos or other material to check radiation, 95 as also are receptacles 13 and 6 and the various connecting-pipes. Tank 1 communicates by 100

means of pipe 27, having a valve set to open toward the tank at a given pressure, with pipe 9 adjacent to the steam-generator.

The oil-tank is preferably made rectangular in form and provided with a covering to obviate the effects of external temperature, and a capacity of about ten gallons would be suitable. The cooling-tank and receptacle 6 may be made cylindrical; but this form is not essential. A capacity of about three gallons for the former and two gallons for the latter would be suitable. The particular form and size of these several tanks and receptacles are not material. The object of the mercury seal is to effectually preclude the possibility of the flame running back from the burner and igniting-vapor in vapor-chamber 13.

The steam-generating coil may have a total pipe-length of four hundred feet or more. It is preferred to construct this generator in "tubular sections," so styled, as commonly practiced in steam boilers and radiators. According to this method two or more tubes arranged side by side are connected at both ends to hollow couplings so constructed that each tube communicates with the interior of the coupling and with the other tubes. Steam entering a coupling passes into each of the tubes, and through them to an opposite coupling, which latter communicates with a similar coupling of another like section, all as will be readily understood by those acquainted with steam-boilers. Instead of a coil as described, a steam-generator of any approved form may be employed without sacrificing the benefits of other parts of the improvement.

In practice two, three, or four inch steam cylinders, connected each to a wheel on the axle and adapted to work under a pressure of from one hundred to one hundred and fifty pounds are preferred. The exhaust-steam is conducted through pipes 30 to the top of the car and discharged through an air-injector, a preferred form of which is indicated at 31. To obviate noise, the steam may be passed out through wire-gauze diaphragms arranged in this injector, or through numerous openings in any approved manner, and the drip can be conducted to the ground by a suitably-arranged pipe. Pipe 30 may be provided with an extension running around or through the car, preferably near the floor, to heat the same in cold weather, said extension being provided with a valve near the main vertical pipe 30, so that it can be cut off when the heating of the car is not desirable.

Air is admitted to the burners either by receiving it through ventilating-pipes from the car or from the open air. In the latter case a wire-gauze or perforated plate can be located beneath the burners to distribute and modify the air-currents. The products of combustion escape through the chimney, as indicated.

The several parts of the apparatus are supported from the car by brackets or hangers in any approved manner, and are preferably in-

closed, doors or openings being provided for ready inspection or for facilitating repairs.

The operation of the apparatus is as follows:

The tank 11 is filled with a vaporizable fuel, preferably gasoline, a reserve being held in tank 2, and tank 1 is filled at stop-cock 29 with water heated to a temperature of 400° Fahrenheit. The several cocks 8, 20, and 24 being opened by lever 26, hot water flows through pipe 7 into the gasoline-heating receptacle 6 and speedily raises the temperature of the gasoline in pipe 12 above the point of vaporization. The vapor passes through the chamber 13 and dip-pipe 14, and through the mercury in the seal into pipe 17, and thence through the main or cross pipe 18 to its burner-tube branches and is there ignited. In the meantime the hot water passes through receptacle 6 and pipe 9, and through the needle-valve 85 opening in the latter into the copper coil, where it is instantaneously converted into highly-heated steam with pressure sufficient to drive the car by means of the cylinders and their connections. When desired, the steam-cock 24, the vapor-cock 20, and the water-cock can be closed by lever 26 shutting off steam from the cylinders, vapor from the burners, and water from heating-receptacle 6, thus obviating dangerous increase of pressure in the generator. The steam in the generator is normally expanded and highly heated, and said generator contains no water, as it only receives momentarily the small quantity that is forced in through the needle-valve opening by pressure from the hot-water tank and which is at once made into steam. To render the apparatus doubly secure, however, the valve at 28 is set to open at any desired degree of pressure greater than that in tank 1, 95 whereby excessive steam-pressure in the generator would be relieved.

The closing of vapor-cock 20 does not shut off the supply from either the lighting devices in the car or from the igniting-burner. To begin the generation of steam it is only necessary to open the several cocks by means of lever 26, whereupon water is immediately forced into the coil and vapor supplied to the burner and ignited by the small permanent flame of 115 the igniting-burner.

Should the hot water admitted to receptacle 6 volatilize more gasoline than required at any time, it will raise the pressure in the coil and force the fluid in the pipe back into the cool- 120 ing-tank 11, where it will be condensed.

As represented, the receptacle 6 is surrounded by an annular vapor-chamber, 13. The latter might, however, be omitted in some cases without departing from the invention, as 125 the vapor-pipe itself could be made of sufficient size and length to contain a reserve of vapor.

An oil-burner of known construction could be substituted for the burner described without sacrificing the advantages of the improvement, in which case the vaporizing-tank 6

would not be used and cock 20 would be placed in the oil-supply pipe and be operated to cut off the fuel-supply. Thus the gasoline or fuel-supply pipe 31 might be provided with a valve 5 and operated by an extension of rod 25, (shown in dotted lines,) said pipe being continued direct to cross-pipe 18, supplying suitable burners. By providing cocks 32 and 33 the apparatus would be adapted to supply either oil or 10 vapor to the burners.

From the foregoing it will be seen that the pressure of both gasoline-vapor and steam is automatically relieved, the former by the action of an excess of pressure in tank 6 and coil 12, whereby the oil is forced back and out of such coil and into the cooling-tank 11 and its supply-pipe, and the latter by means of relief-valve 28; that the supply of fuel, the supply of steam, and the generation of the latter can 15 be instantly stopped or started; that the fire can be instantly quenched or kindled; that no water is held in the generator; that no ashes are thrown upon the street and no steam into the air, and that every operation except that 20 of filling the tanks at the station can be controlled by a person of ordinary intelligence by means of the single operating-lever. The invention, however, is not limited to a single operating-lever, as other mechanical powers 25 might be substituted, and also a separate lever or other instrumentality might be used for each valve. These operating devices can conveniently be duplicated in such manner that they may be controlled from either platform, 30 as desired—as, for example, by extending rod 25 to both platforms and providing it with a lever at each end.

It is obvious that the herein-described improvements do not relate to the particular car, 40 but are applicable generally to vehicles using a steam-motor; and further, that neither the use of mercury instead of other suitable sealing-liquid, nor the particular location or form of the condenser, oil-tank, and hot-water reservoir, nor 45 the particular form of valves, steam-generating coil, and steam-cylinder are of the essence of my invention, which includes these elements in the form and manner shown and all well-known equivalents for every part herein set forth acting in substantially the same way to 50 produce like results.

Heretofore in steam-generators using a liquid fuel devices for regulating and cutting off the supply of water and fuel have been arranged to act simultaneously through connected mechanism, and such matters are not herein claimed. In my apparatus connected mechanism is employed which simultaneously closes a valve or equivalent in the water-pipe, 55 fuel-pipe, and also in the steam-pipe between the generator and the steam-cylinder.

Having thus described my invention, what I claim, and desire to secure by Letters Patent, is—

1. The combination of the hot-water-storage tank, a pipe connecting it with the steam-

generator provided with a pressure-reducing valve, a fuel-supply pipe provided with a valve, the burner, and the steam-generator, substantially as set forth, whereby water may be 70 forced by the pressure of the storage-tank into the generator and instantaneously converted into steam, and whereby fuel for the heating-burner may be instantly cut off.

2. The combination of the hot-water-storage tank, a pipe connecting it with the steam-generator provided with a pressure-reducing valve, a fuel-supply pipe provided with a valve, the burner, the steam-generator, and an igniting-burner, substantially as set forth, 80 whereby water may be forced by the pressure of the storage-tank into the generator and instantaneously converted into steam, and whereby fuel for the heating-burner may be 85 instantly cut off, and whereby also the fuel may be immediately ignited upon the opening of the valve in the supply-pipe.

3. In an apparatus for propelling cars, the combination of the oil and water tanks, the vaporizing and cooling receptacles, the steam-generator and burner, and pipes connecting the water-tank with the vaporizing-tank and the latter with the generating-coil, pipes extending from the oil-tank through the vaporizing water-receptacle to the burner, and a 90 needle-valve in the water-pipe between the generator and the vaporizing-receptacle, substantially as specified.

4. The combination of vaporizing-receptacle, vapor-pipe, mercury seal, and burner with 100 a water-pipe having a needle-valve and a steam-generating coil, substantially as specified.

5. The combination of the water-supply pipe and its valve, the fuel-supply pipe and 105 its valve, the burner, the steam-generator and steam-pipe having a valve, the several valves being connected to one operating mechanism, whereby the valves can be simultaneously opened or closed, substantially as specified. 110

6. The combination of the hot-water-supply pipe and its valve, the hot-water receptacle, the fuel-supply pipe and its valve, the burner, and the steam generator and cylinder, the several valves being connected to one operating 115 mechanism, whereby the valves can be simultaneously opened or closed, substantially as specified.

7. The combination of a water-supply pipe having a needle-valve with a steam-generator 120 and steam-pipe, a vapor-pipe, and mercury seal, a burner and valves operated by a single lever to close both the steam and vapor pipes, substantially as specified.

8. The combination of the water-tank, the water-supply pipe with needle-valve, the steam generator and pipe, pipe 27, having a pressure-valve opening toward the tank, a vapor pipe and burner, and valves in the vapor and steam pipes, substantially as specified, 125 whereby, when the valves are closed, the fuel-supply is cut off and means are provided for 130

relieving any accidental excess of pressure in the generator.

9. In a street-car, the combination of the steam generator and pipe, vapor-burner, and vapor-supply pipe, both pipes having valves operated by a single lever, the steam-cylinder, the exhaust-steam pipe, and the condenser for exhaust-steam, substantially as specified.

10. The combination of the vapor-pipe having a branch connected with an illuminating-burner, a branch connecting with a lighting-burner, the main vapor-burner, the steam-generator, the valves in the vapor and steam pipes, the vapor-pipe valve being located be-

15 tween the branches of the vapor-pipe and the main burner, whereby the fuel can be cut off from the main burner without cutting off the other burners, substantially as specified.

11. The combination of the hot-water tank, 20 the steam-generator, the vapor-burner, and pipes provided with valves, whereby the com-

bustion of vapor and the generation of steam may be simultaneously controlled, substantially as specified.

12. The hot-water tank, a steam-generator, 25 a pipe connecting the tank and generator provided with a pressure-reducing valve, in combination with a tank for a vaporizable fuel, a vapor-generator, a pipe provided with a vapor-controlling valve extending from said vapor-generator to a burner, all substantially as specified, whereby hot water may be injected into the generator and instantly converted into steam, and whereby the fire of the burner may be instantly extinguished.

30 In testimony whereof I affix my signature in presence of two witnesses.
